UNITED STATES PATENT OFFICE.

JOHANNES TH. PEDERSEN, OF FLUSHING, NEW YORK.

SIGHT-FEED DEVICE.

1,096,561.

Specification of Letters Patent. Patented May 12, 1914.

Application filed November 17, 1911. Serial No. 660,755.

To all whom it may concern:

Be it known that I, JOHANNES TH. PEDERSEN, a citizen of the United States, residing at Flushing, borough of Queens, city and State of New York, have invented an Improvement in Sight-Feed Devices, of which the following is a specification.

My present invention relates to a lubricating apparatus, and more particularly to devices by which the lubricant may be observed as the same is fed to the parts to be lubricated, and while adapted for use in any lubricating apparatus where it is desired to see the feed, the device of my present invention is particularly adapted for motor vehicles and other similar uses where the apparatus is subject to a greater or less amount of vibration.

Heretofore various sight-feed devices have been employed, and in some of which provision has been made for regulating the feed, but so far as I am aware difficulty has been experienced with this type of sight-feed devices when employed where there is any appreciable amount of vibration because of the tendency of the vibration is to change or vary the position of the feed regulating means. Other of these sight-feed devices are very liable to leak around the glass parts, and the object of my present invention is to overcome these difficulties.

In carrying out my present invention with this object in view, I preferably employ a receptacle with a cover therefor, a delivery cock within the receptacle, a device by which the flow from the delivery cock is regulatable and means for holding said device in position, as will be hereinafter more particularly described.

In the drawing Figure 1 is a front elevation of my improved sight-feed device. Fig. 2 is a vertical section on line α , α , Fig. 1. Fig. 3 is an elevation of the regulating or adjusting screw. Fig. 4 is a sectional plan of the feed pipe connection at line x^1 , x^1 , Fig. 2. Fig. 5 is a plan of the same, Fig. 6 is a front elevation of a modified form of feed pipe connection and Fig. 7 is a side elevation of the same. Fig. 8 is an elevation of a modified form of the adjusting or regulating screw, and Fig. 9 is a plan view of the spring for the adjusting screws.

Similar letters and numerals of reference indicate similar parts.

Referring to the drawing, 10 designates the casing, which, as illustrated, is prefer-

ably rectangular in front elevation, although I do not limit myself to this configuration of the casing. The casing comprises a back member 11, the top member 12, the bottom member 13, which is preferably inclined, sides 14 and 15 and a front member 16, which is also preferably inclined and provided with a circular opening, the flange forming which is adapted to receive a cover 17 fitted with a glass or other transparent body 18 through which the interior of the casing may be seen. The back member of the casing is preferably provided with a lug 19 by means of which, and a clasp screw 20, the casing may be located and secured in position to the dashboard of an automobile or other support.

Within the casing I preferably employ a tubular T-shaped body 21, a limb or member 22 of which is exteriorly screw-threaded, adapted to pass through an opening provided therefor in the back of the casing, and to be secured in this position by means of a nut 23, turned down on the member 22 or otherwise. Fig. 2 also shows this screw-threaded member 22 as also adapted to receive a coupling nipple 24 by means of which a feed or supply pipe 25 is connected thereto.

Secured to and preferably depending from the cross-arm of the T body there are two delivery cocks 26 and 27, and within the casing I preferably employ a partition 28 dividing the same into two compartments, as shown at a , b , respectively, the delivery cock 26 extending into the compartment a and the delivery cock 27 extending into the compartment b . Each delivery cock interiorly in a position immediately below the level of the bore of the cross-arm of the T body is provided with a tapering seat 29.

As shown in connection with Figs. 1, 2 and 3, I prefer to employ an adjusting screw 30 at the end of the shank 31, of which is a tapering valve 32; the screw-threaded portion of the shank 31 being adapted to engage the screw threads within the bore of the delivery cock in which the adjusting screw is inserted, so that the adjusting screw may be turned down, causing the tapering valve 32 to seat against the valve seat 29, it being understood that each delivery cock is provided with one of these adjusting screws having a tapering valve at the end thereof. The shank 31 of each adjusting screw is also provided with a circumferential recess 33, and in the form of indicating device

illustrated, a spring 34, made of sheet metal or other similar material, is secured centrally in position to the top member of the casing and between the pair of adjusting screws, and at its extremities this spring 34 is bifurcated, providing recesses 36 which are adapted to receive the circumferential recessed portions of the adjusting screws and to frictionally engage the adjacent portions of the said adjusting screws. It will be apparent that by the employment of this spring 34, that when turned to the desired position any adjusting screw will be there frictionally maintained against accidental displacement due to the vibration of the apparatus, vehicle or other support of the device. The lower portion of the casing is provided with perforated lugs 37 to which outlet connections 38 may be secured, the outlet connections, of course, leading to the parts of the apparatus to be lubricated.

Referring to the form of my invention shown in Figs. 6, 7 and 8, it will be seen that the delivery cocks 39 and 40 may depend directly beneath the cross member of the tubular T-shaped body, and that instead of employing adjusting screws which extend through the casing and are operated exteriorly, I may employ adjusting screws 41, all of which lie entirely within the casing, the position of which is adjusted by the insertion of a screw-driver within the casing upon the removal of the cover 17 or in some other desired manner.

I claim as my invention:

1. A sight feed device comprising a casing, a cover therefor in part transparent and through which the interior of the casing may be observed for substantially the entire width thereof, delivery cocks within the casing, a common intake extending through a wall of the casing and to which the said cocks are connected, a partition extending upwardly from the bottom of the casing to a point appreciably above the orifices of the said delivery cocks so as to divide the interior of the casing into separate compartments for the lubricant from each of the said delivery cocks, and separate devices for delivering the lubricant from each of the said compartments.

2. A sight feed device comprising a casing the bottom of which is inclined, a cover for the casing which in part is transparent and through which the interior of the casing may be observed for substantially the entire width thereof, a common inlet for a lubricant, branches extending from the inlet transversely of the casing and interiorly thereof, delivery cocks connected in the said branches, a partition extending from the bottom of the casing to a point a substantial distance above the orifices of the said de-

livery cocks and between the same, thereby dividing the casing interiorly into separate compartments, and separate devices for delivering the lubricant from each of the said compartments.

3. A sight feed device comprising a casing the bottom of which is inclined, a cover 70 for the casing which in part is transparent and through which the interior of the casing may be observed for substantially the entire width thereof, a common inlet for a lubricant, branches extending from the inlet transversely of the casing and interiorly thereof, delivery cocks connected in the said branches, a partition extending from the bottom of the casing to a point a substantial distance above the orifices of the said delivery cocks and between the same thereby dividing the casing interiorly into separate compartments, a device for regulating the feed through each delivery cock, means for maintaining each delivery cock in position 85 against accidental displacement, and separate devices for delivering the lubricant from each of the said compartments.

4. A sight feed device comprising a casing the bottom of which is inclined, a cover for 90 the casing which in part is transparent and through which the interior of the casing may be observed for substantially the entire width thereof, a common inlet for a lubricant, branches extending from the inlet 95 transversely of the casing and interiorly thereof, delivery cocks connected in the said branches, a partition extending from the bottom of the casing to a point a substantial distance above the orifices of the said delivery cocks and between the same thereby dividing the casing interiorly into separate compartments, a device for regulating the feed 100 through each delivery cock, means for maintaining each delivery cock in position against accidental displacement, and separate devices for delivering the lubricant from each of the said compartments.

5. A sight-feed device, comprising a casing, a feed pipe extending into the same, a delivery cock, an adjusting screw the shank 110 of which is provided with a circumferential recess and which shank terminates in a tapering valve, and a spring secured to the casing and having a recessed end adapted to receive the circumferential recessed portion 115 of the shank of the adjusting screw, the frictional engagement between which parts maintains the adjusting screw in position against accidental displacement.

Signed by me this 14th day of November, 120 1911.

JOHANNES TH. PEDERSEN.
